UNITED STATES PATENT OFFICE.

FRANK L. GORMLEY, OF BROOKLINE, MASSACHUSETTS, ASSIGNOR TO A. O. NORTON, INC., OF BOSTON, MASSACHUSETTS, A CORPORATION OF MAINE.

SPEED-RETARDING DEVICE FOR LIFTING-JACKS.

1,395,340.

Specification of Letters Patent.

Patented Nov. 1, 1921.

Application filed July 22, 1920. Serial No. 398,114.

To all whom it may concern:

Be it known that I, FRANK L. GORMLEY, a citizen of the United States of America, and a resident of Brookline, in the county 5 of Norfolk and Commonwealth of Massachusetts, have invented certain new and useful Improvements in Speed-Retarding Devices for Lifting-Jacks, of which the following is a specification.

10 This invention relates to speed retarding devices for lifting jacks and the like and particularly to devices of this character which are adapted to be applied to the high speed end of a train of gears actuated only 15 during the lowering of the load-supporting member.

The object of the invention is the production of a simple mechanism which may be applied readily to the usual worm shaft 20 of a lifting jack and which will effectually control the speed of the same, said mechanism being provided with means whereby the speed may be varied as desired.

The invention consists of two dash pots 25 having pistons therein connected to the worm shaft in such a manner that said pistons will always be moving in opposite directions during the operation of the jack, said dash pots and pistons being provided 30 with suitable valves whereby the air in advance of each piston has a limited outlet from said dash pots thereby providing means for maintaining the rotation of said worm shaft at a uniform speed.

35 The invention further consists of connecting the air outlets from both dash pots with a single discharge pipe having a valve therein which is adapted to regulate the discharge of air from said dash pots and 40 thereby vary the speed of rotation of the piston-actuating member.

The invention further consists in certain 45 novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which 50 the invention consists can be variously arranged and organized and the invention is

not limited to the precise arrangement and organization of these instrumentalities as herein shown and described, except as required by the scope of the appended claims.

Of the drawings:

Figure 1 represents a horizontal section of a lifting jack embodying the features of the present invention, the cutting plane being on line 1, 1, on Fig. 2.

Fig. 2 represents a vertical section of the 65 same on line 2, 2, on Fig. 1.

Fig. 3 represents an elevation of the cover plate with the various actuating devices secured thereto, the operating shaft being cut 70 in section.

Fig. 4 represents a horizontal section on line 4, 4, on Fig. 3.

Fig. 5 represents an elevation of the dash pot mechanism, partially in section and drawn to an enlarged scale, with the various parts in inoperative position and the controlling valve closed.

Fig. 6 represents a similar view with the controlling valve partially opened and the various parts in operative opposition.

Fig. 7 represents an elevation of the manually controlled braking mechanism with a portion thereof broken in section, and

Fig. 8 represents an elevation of the device for controlling the action of the brake 85 mechanism.

Similar characters indicate like parts throughout the several figures of the drawings.

In the drawings, 10 represents a suitable 90 base supporting a stationary standard 11 over the outer periphery of which is fitted a movable sleeve 12, to the upper end of which is threaded a cap 13.

In the upper end of the standard 11 is 95 mounted a nut 14 to which is threaded a lifting screw 15 having splined to its upper reduced end a bevel gear 16 with which meshes a bevel gear 17 formed upon or secured to a revoluble shaft or spindle 18, 100 the outer end of which is provided with a suitable operating mechanism 19 of any well-known construction.

Between the upper face of the bevel gear 16 and the inner face of the cap 13 are two 105 annular plates 20, 21, between which are interposed a plurality of anti-friction members 22.

The movable member 12 is provided on one side with a flanged projection 24 having 110

a removable plate 25 secured thereto by bolts 25^x.

The plate 25 is provided with a bearing 26 for the spindle or shaft 18 and secured to 5 the hub of the gear 17 is a ratchet wheel 27.

The bearing 26 extends through a cylindrical boss 28 on the inner face of the plate 25 and on this boss 28 is loosely mounted the gear wheel 29 having secured to one face 10 thereof a plurality of pawls 30 coacting with said ratchet wheel 27.

The gear 29 is provided with a plurality of projections 31 to the outer ends of which is secured a ring 32 between which and said 15 gear the pawls 30 are positioned.

From the back of the free end of each pawl 30 extends a lug 33 on which is disposed a helical spring 34 the outer end of which bears against one of the projections 20 31 and retains said pawls 30 in engagement with said ratchet wheel 27 under normal conditions.

Beneath the gear wheel 29 is a revoluble shaft 35 having secured thereto a pinion 36 25 meshing with said gear 29 and driven thereby when the movable member 12 of the jack is being lowered.

The shaft 35 has also secured thereto a worm wheel 37 which meshes with a worm 30 38 revoluble in bearings 39 in the bracket 40 secured to the inner face of the removable plate 25 by screws 40^x.

To the reduced end 41 of the worm 38 is secured a brake disk 42 with the periphery 35 of which coacts two brake members 43 pivoted at 44 to the bracket 40.

The lower end of each brake member 43 is provided with a recess 45 in which is positioned one end of a helical spring 46 the 40 opposite ends of said springs being disposed in the recesses 47 and 48 in the removable plate 25 and bracket 40.

Between the lower adjacent ends of the 45 brake members 43 is positioned a flat sided projection 49 formed upon the actuating lever 50.

A portion of the flat sided projection 49 is cylindrical and positioned in a cylindrical hole in the flange of the removable plate 25.

50 The springs 46 normally retain the brake members in contact with the periphery of the disk 42 and prevent its rotation until the actuating lever 50 is moved to cause said flat sided projection 49 to separate said brake members 43 and remove them from contact with the disk 42.

As thus far described the jack is the same as that shown and described in Letters Patent No. 1,324,345 issued to me Dec. 9, 1919.

60 In the present instance the governor mechanism described in the above-entitled patent is dispensed with and a speed retarding device of an entirely different character is substituted therefor.

65 This speed retarding device consists of a

disk 51 secured to the reduced end 52 of the worm 38, said disk 51 having a lateral stud 53 extending through a slot in a reciprocating member 54.

Each end of the member 54 is pivotally 70 connected at 55 to a piston 56 adapted to reciprocate in a cup-shaped member or dash pot 57.

Each dash pot 57 is provided with an air passage 58 communicating with the inner 75 end of said dash pot and normally closed by the spring-pressed valve 59.

The opposite ends of the passages 58 communicate with the pipes 60 both connecting with a T 61, one branch of which has a discharge pipe 62 extending therefrom, the outer end of which is provided with a valve 63 by which the amount of air to be forced from the dash pots 57 may be controlled.

Each piston 56 is provided with one or 85 more spring-pressed valves 64 adapted to be opened on the out-stroke of the piston to admit air to said dash pots 57.

On the in-stroke of the pistons 56, the valves 64 will be closed and the valves 59 90 opened thus providing a means whereby the air in the dash pots 57 may be expelled therefrom.

The amount of air expelled will depend upon the amount of opening of the controlling valve 63.

The air expelled from one dash pot 57 is prevented from entering the other dash pot by means of the valve 59 and therefore the only outlet therefor will be through pipe 62 100 and controlling valve 63.

It will be noted that at all times one piston is moving inward and when the controlling valve 63 has been set for a desired speed, the rotation of the worm 38 will be retarded to 105 conform to this predetermined speed.

As a consequence the rotation of the worm 38 will be at a uniform speed for any one setting of the valve 63, but a variation in speed may be secured by manually actuating the said valve 63 to provide a greater or lesser opening as desired.

The removable cover plate 25 is provided with a support 67 for the dash pots 57 and a semi-cylindrical recess into which portions 115 of the brake mechanism extend.

When the cover plate 25 is removed from the flanged projection 24 all of the devices for controlling the lowering of the movable member 12 are removed therewith.

120 The shaft 71 of the worm 38 has a cup-shaped member 72 mounted thereon abutting the governor housing 73 and a washer 74 abutting the end of the worm 38 and between the washer 74 and the cup-shaped member 72 are a plurality of anti-friction members 75 adapted to take care of the end thrust of the worm 38 during the lowering of the jack.

125 The pitch of the worm 38 is such that 130

during the rotation of the worm gear 37 rotary movement will be imparted to the shaft 71 and the disks 42, 52.

When the brake members 43 are removed 5 from the brake disk 42, the jack is free to lower under its load.

Should the jack under an excessive load start to rotate the worm 38 at too great a speed for safety the speed will be retarded 10 by means of the pistons 56 reciprocating in the dash pots 57 and the worm will be compelled to rotate at its normal predetermined speed.

When pressure is released from the actuating lever 50, the springs 46 will force the brake members 43 into contact with the periphery of the disk 42 and prevent further lowering of the jack.

When it is desired to raise the movable 20 member 12, the operating mechanism 19 is manipulated to turn the spindle 18 and gear 17 formed thereon in the direction of the arrow *a* on Fig. 3 of the drawing.

When this is done the ratchet 27 will 25 freely pass the pawls 30 without actuating the spur gear 29.

While lifting the load the operating mechanism will act directly upon the movable member 12 through the gears 17 and 16 and 30 screw 15 without affecting the speed retarding and braking devices.

When the weight has been lifted sufficiently, it will be retained in its elevated position by means of the friction members 43 35 coacting with the brake disk 42 and preventing the rotation of the worm 38.

When it is desired to lower the load supported by the movable member 12, the friction members 43 are removed from contact 40 with the disk or wheel 42 by pressing upon the arm or lever 50 and with the pawls 30 in engagement with the teeth of the ratchet 27, the gear 29, pinion 36, worm wheel 37 and worm 38 will be driven by the rotation of 45 the gear 17 and its spindle 18.

The pitch of the worm thread is such as to permit the jack to start automatically to descend under its own load when its brake is released.

50 Should an excessive load be upon the cap 13 so that member 12 starts to move downwardly too rapidly, its movement will be arrested by the action of the speed retarding device.

55 If it is desired to entirely stop the lowering of the load, pressure is removed from the actuating lever 50 and the brake members 43 will be forced into contact with the disk 42.

60 The multiplication of the braking power through the high ratio gearing and through the worm and worm wheel will serve to make possible the quick and easy stoppage by a light pressure of the brake, of the descending jack at any point.

It is believed that the operation and many advantages of the invention will be readily understood without further description.

Having thus described my invention, I claim:

1. In a combination with a lifting jack adapted to lower under the weight of the load and including a load-supporting member, a shaft adapted to be rotated in one direction only, and mechanism between said load-supporting member and said shaft for imparting rotary movement to said shaft during the lowering operation at a speed greater than that of said load-supporting member; a member secured to and revolute 70 with said shaft; a dash pot; and a piston therein adapted to be reciprocated by said revolute member.

2. In a combination with a lifting jack adapted to lower under the weight of the load and including a load-supporting member, a shaft adapted to be rotated in one direction only, and mechanism between said load-supporting member and said shaft for imparting rotary movement to said shaft 80 during the lowering operation at a speed greater than that of said load-supporting member; a member secured to and revolute with said shaft; a dash pot having an air outlet at its inner end; a piston therein 85 adapted to be reciprocated by said revolute member; and means for controlling the discharge of air through said outlet.

3. In a combination with a lifting jack adapted to lower under the weight of the load and including a load-supporting member, a shaft adapted to be rotated in one direction only, and mechanism between said load-supporting member and said shaft for imparting rotary movement to said shaft 100 during the lowering operation at a speed greater than that of said load-supporting member; a member secured to and revolute with said shaft; a dash pot; a piston therein adapted to be reciprocated by said revolute 105 member; a valve in said piston adapted to close on the in-stroke of the piston and open on the out-stroke thereof; and means for controlling the discharge of air through said outlet.

4. In a combination with a lifting jack adapted to lower under the weight of the load and including a load-supporting member, a shaft adapted to be rotated in one direction only, and mechanism between said load-supporting member and said shaft for imparting rotary movement to said shaft 120 during the lowering operation at a speed greater than that of said load-supporting member; a member secured to and revolute with said shaft; two dash pots having air outlets at their inner ends; pistons in said dash pots; mechanism between said revolute member and said dash pots for simultaneously moving one piston inwardly and 125 130

the other outwardly; and means for controlling the discharge of air through each outlet during the instroke of each piston.

5. In a combination with a lifting jack 5 adapted to lower under the weight of the load and including a load-supporting member, a shaft adapted to be rotated in one direction only, and mechanism between said load-supporting member and said shaft for 10 imparting rotary movement to said shaft during the lowering operation at a speed greater than that of said load-supporting member; a member secured to and revolute with said shaft; two dash pots having air 15 outlets at their inner ends; pistons in said dash pots; mechanism between said revolute member and said dash pots for simultaneously moving one piston inwardly and the other outwardly; and a valve common 20 to both dash pots for controlling the discharge of air through each outlet during the in-stroke of each piston.

6. A speed retarding device for load-lifting apparatus consisting of a load-supporting member and a revolute shaft positively 25 driven in one direction only by the lowering of said load-supporting member; a member secured to and rotatable with said shaft; two dash pots having air outlets at their 30 inner ends; pistons in said dash pots; mechanism between said revolute member and said pistons for simultaneously moving one piston inwardly and the other outwardly; and means for controlling the discharge of 35 air through each outlet during the instroke of each piston.

7. A speed retarding device for load-lifting apparatus consisting of a load-supporting member and a revolute shaft positively 40 driven in one direction only by the lowering of said load-supporting member; a member secured to and rotatable with said shaft; two dash pots having air outlets at their 45 inner ends; pistons in said dash pots; mechanism between said revolute member and said pistons for simultaneously moving one piston inwardly and the other outwardly; and a valve common to both dash pots for controlling the discharge of air through 50 each outlet during the in-stroke of each piston.

8. A speed retarding device for load-lifting apparatus consisting of a load-support-

ing member and a revolute shaft positively 55 driven in one direction only by the lowering of said load-supporting member; a member secured to and rotatable with said shaft; two dash pots having air outlets at their 60 inner ends; pistons in said dash pots; mechanism between said revolute member and said pistons for simultaneously moving one piston inwardly and the other outwardly; valves in said outlets adapted to be closed 65 during the outstroke of the pistons and opened during the in-stroke thereof; and means for controlling the discharge of air through each outlet.

9. A speed retarding device for load-lifting apparatus consisting of a load-supporting member and a revolute shaft positively 70 driven in one direction only by the lowering of said load-supporting member; a member secured to and rotatable with said shaft; two dash pots having their outlets at their 75 inner ends; pistons in said dash pots; mechanism between said revolute member and said pistons for simultaneously moving one piston inwardly and the other outwardly; valves in said outlets adapted to be closed during the out-stroke of the pistons and 80 opened during the in-stroke thereof; valves in said pistons adapted to be closed during the in-stroke of said pistons and opened during the out-stroke thereof; and means for controlling the discharge of air through 85 each outlet.

10. A speed retarding device for load-lifting apparatus consisting of a revolute member; two dash pots having air outlets 90 at their inner ends; pistons in said dash pots; a bar connecting said pistons having an elongated transverse slot therein; a stud on said revolute member extending through said slot and adapted to impart reciprocal movement to said bar and 95 pistons; valves in said outlets adapted to be closed during the out-stroke of the pistons and opened during the in-stroke thereof; and means for controlling the discharge of air through 100 each outlet.

Signed by me at 746-7 Old South Bldg., Boston, Mass., this 17th day of July, 1920.
